Roland H. Goldston, Jr., 504 Glendale Drive,
Wilson, N.C. 27893

Filed Jan. 17, 1968, Ser. No. 10,191

Term of patent 14 years

Int. Cl. D12—99

U.S. Cl. D41—1

FIG. 1 is a top plan view of a bumper engaging unit for truck attached lifting and towing devices or the like showing my new design;

FIG. 2 is a rear elevational view of such design;

FIG. 3 is a section taken through lines 3—3 of FIG. 1; and

FIG. 4 is a perspective of said design.

The bottom of my design is a mirror image of the top plan view with the elimination of the bracing gussets.

I claim:

The ornamental design for a bumper engaging unit for truck attached lifting and towing devices or the like, as shown and described.
